UNITED STATES PATENT OFFICE.

JAMES R. HAYDON, OF CHICAGO, ILLINOIS.

AIR-PROPELLER.

1,141,337.

Specification of Letters Patent.

Patented June 1, 1915.

Application filed September 3, 1914. Serial No. 859,941.

To all whom it may concern:

Be it known that I, JAMES R. HAYDON, a citizen of the United States, and a resident of Chicago, in the county of Cook and State 5 of Illinois, have invented certain new and useful Improvements in Air-Propellers; and I do hereby declare that the following is a full, clear, and exact description thereof, reference being had to the accompanying 10 drawings, and to the characters of reference marked thereon, which form a part of this specification.

This invention relates to a novel air propeller for driving or lifting flying machines, 15 boats or other conveyances, and the invention consists in the matters hereinafter set forth and more particularly pointed out in the appended claims.

Among the objects of the invention is to 20 provide a propeller of such construction and arrangement as to increase the power thereof to drive or lift the machine relatively to the weight of the propeller as compared to present practice.

25 A further object of the invention is to provide a propeller of such construction as to render it practicable to build and operate a propeller of considerably larger diameter than feasible under present practice.

30 A further object of the invention is to provide a propeller having a series of blades which are mounted on radial elements that transmit the driving power from the motor shaft, with means whereby the radial elements 35 are tensioned by centrifugal action due to the rotation of the propeller, whereby the radial elements may be made light, as compared to their strength, to transmit the driving power of the propeller shaft to the 40 blades.

A further object of the invention is to provide a high power propeller having a small resistance to its passage through the air in the direction of movement of the machine.

45 A further object of the invention is to provide, in an air propeller, blades which are free to move on their supports with controlling means to hold the blades properly presented to the air for the most effective application of motive power.

50 Other objects of the invention are to improve and simplify propellers, as will hereinafter appear.

In the drawings:—Figure 1 is a plan or 55 elevation of a propeller embodying my invention. Fig. 2 is an enlarged detail of one

of the blades and associated parts. Fig. 3 is an edge elevation of one of the blades and its controlling vane, with the peripheral supporting member shown in dotted lines. Fig. 4 is a detail showing a modification.

A propeller embodying my invention comprises a central hub 10, radial elements 11 made of light rods, steel cable or the like, attached at their inner ends thereto, blades 12 carried by the outer ends of said radial elements and means at the outer ends of said radial elements which act by centrifugal force, due to the rotation of the propeller, to tension the radial elements so as to maintain them in proper radial relation to each other to transmit the driving power of the motor, through the shaft 14, to the blades. The blades may be made of any suitable curvature and arranged at such angle relatively 70 to the plane of rotation of the propeller as to present the most effective surface to the air to drive the machine. The means which act by centrifugal action to tension the radial elements may consist of weights 14', 75 separate from the blades and attached to the radial elements, as shown in Figs. 1 and 2, or the blades themselves, as the blades 15 shown in Fig. 4, may be made of suitable weight as to act as centrifugally acting tensioning 80 factors.

In one embodiment of the invention the blades 12 are pivotally mounted on the radial elements 11, said blades being provided with hollow hubs 16 which fit loosely on the radial elements, whereby the blades upon receiving a dynamic pressure upon their driving faces are free to angularly adjust themselves relatively to their plane of rotation so as to properly present their driving 90 faces to the air. As a result, when the propeller is in action the blades are balanced with respect to rotation about their axes. When the blades are thus loosely mounted on the radial elements they may be provided with controlling vanes 17 which may be made parts of or be fixed to the blades and extend rearwardly therefrom in the plane of rotation of the propeller. As herein 95 shown, the blades are fixed rigidly to or are made integral with the extensions 18 of the hubs of the blades and are located at the sides of the blades. In some instances, the controlling vanes may trail behind the blades, but their location at the sides thereof is favorable for efficient blade control, inasmuch as they thereby travel in areas of air 100 105 110

little or in no wise disturbed by the blades. By reason of the fixed connection of the vanes to the blades, and by reason of the fact that the vanes are made considerably longer than the blades and travel in the plane of the propeller, the selected angle of presentation of the blades to the air will be maintained notwithstanding the fact of the pivotal connection of the blade with the radial elements.

In order to hold the blades in proper position when the propeller is at rest, I may provide a circumferential ring 20 of light gage and sufficiently wide to give the desired strength thereto. The radial elements loosely extend at their outer ends through openings in said ring so as to be free to be tensioned by centrifugal force upon rotation of the propeller. As shown in Figs. 1 and 2, the weights 14' are located outside of the hoop or ring and said weights serve as stops to prevent disconnection of the radial elements from the ring. Shoulders 19 on the radial elements prevent the blades and vanes from moving inwardly on the radial elements when the propeller is at rest. As shown in Fig. 4, wherein the blades 15 constitute the weights, said weights, and preferably also their controlling vanes, are located exterior to the ring 20. The ring being made of light gage presents little resistance to the travel of the propeller through the air. Both the weights and the hubs of the blades are of such contour as to present a minimum resistance to their passage through the air.

The propeller described may be rotated in a vertical plane to drive the machine forwardly through the air, or may be rotated in a horizontal plane to lift the machine, the machine thus sustained being driven forwardly by a suitable propeller of the type herein shown or any other suitable type. In the latter construction, the machine may be sustained by the combined action of fixed lifting planes and said blades which latter become, in such suggested construction, rotating supporting elements. In some instances, the blades may be fixed to the radial elements, or without pivotal action thereon. In this event, the radial elements may rotatively yield sufficiently to permit the blades to be adjusted to the air.

If it should be found that an undue stress be imposed on the shaft when the conveyance which the propeller is driving is turning from a straight course, the periphery of the propeller may be arranged to be supported by rollers carried on parts fixed to the conveyance and normally out of contact with the propeller, but sufficiently close to engage the peripheral ring upon the occasion

of a slight deflection of the propeller out of its plane.

I claim as my invention.

1. An air propeller comprising a hub, centrifugally tensioned radial elements fixed at their inner ends thereto, and blades pivotally carried by the outer ends of said elements and balanced with respect to rotation about their axes.

2. An air propeller comprising a hub, centrifugally tensioned radial elements fixed at their inner ends thereto, blades pivotally carried at the outer ends of said elements and balanced with respect to rotation about their axes and air controlled means for maintaining the angular position of the blades.

3. An air propeller comprising a hub, centrifugally tensioned radial elements fixed at their inner ends thereto, blades pivotally mounted on said radial elements and balanced with respect to rotation about their axes and vanes controlling the angle of presentation of the blades to the air.

4. An air propeller comprising a hub, centrifugally tensioned radial elements fixed at their inner ends thereto, blades carried by the outer ends of said elements, and means to support said radial elements and the blades when the propeller is at rest.

5. An air propeller comprising a hub, centrifugally tensioned radial elements fixed at their inner ends thereto, blades carried by the outer ends of said elements, and a circumferential supporting ring with which the radial elements have sliding connection.

6. An air propeller comprising a hub, centrifugally tensioned radial elements fixed at their inner ends thereto, blades pivotally carried by the outer ends of said elements, and balanced with respect to rotation about their axes and controlling means acting on the blades to hold them properly presented to the air.

7. An air propeller comprising a hub, radial elements fixed at their inner ends thereto and blades pivotally supported on the outer ends of said radial elements and balanced with respect to rotation about their axes, and blade controlling vanes fixed to said blades and trailing behind said blades in the plane of rotation of the radial elements.

In testimony, that I claim the foregoing as my invention I affix my signature in the presence of two witnesses, this 31st day of August, A. D. 1914.

JAMES R. HAYDON.
